(57) **CLAIM**

The ornamental design for a display screen with an animated graphical user interface, as shown and described.

DESCRIPTION

FIG. 1 is a first image in a sequence of a display screen with an animated graphical user interface; FIG. 2 is a second image thereof; FIG. 3 is a third image thereof; and, FIG. 4 is a fourth image thereof.

The outermost broken lines, even dashed broken lines, illustrate portions of the display screen with an animated graphical user interface and form no part of the claimed design.

The appearance of the transitional image sequentially transitions between the images shown in FIGS. 1-4. The process or period in which one image transitions to another image forms no part of the claimed design.
